UNITED STATES PATENT OFFICE.

ZENOS PORTER, OF HOLLIDAY, UTAH.

PLOW.

1,113,047.

Specification of Letters Patent.

Patented Oct. 6, 1914.

Application filed June 10, 1913. Serial No. 772,809.

To all whom it may concern:

Be it known that I, ZENOS PORTER, a citizen of the United States, residing at Holliday, in the county of Salt Lake and State 5 of Utah, have invented new and useful Improvements in Plows, of which the following is a specification.

This invention relates to plows, and it has particular reference to walking plows of the 10 reversible type.

One object of the invention is to produce a reversible walking plow wherein a base constituting a land side bar supports an upright about which a sleeve constituting a 15 standard rotates, said sleeve or standard being associated with the beam, the handles and with a locking lever.

A further object of the invention is to produce a plow of the type described wherein 20 the right and left hand mold boards are provided with hingedly supported wings and with means for reversing the position of said wings when the beam and the handles are reversed.

25 Further objects of the invention are to simplify and improve the construction and assembling of the parts of the device.

With these and other ends in view which 30 will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention, it being, however, understood that no limitation is necessarily made to the precise structural details therein exhibited, 40 but that changes, alterations and modifications within the scope of the claims may be resorted to when desired.

In the drawings,—Figure 1 is a top plan view of a plow constructed in accordance 45 with the invention. Fig. 2 is a side elevation of the same with parts broken away. Fig. 3 is a top plan view, showing the device in the act of being reversed. Fig. 4 is a plan view of the base portion of the device. Fig. 5 is a detail view in side elevation 50 showing the sleeve or standard carrying beam, detached. Fig. 6 is a rear elevation of the same. Fig. 7 is a horizontal sectional detail view taken on the line 7—7 in Fig. 2.

Fig. 8 is a detail view showing the mold 55 board wings detached.

Corresponding parts in the several figures are denoted by like characters of reference.

The base bar 10 is formed with frogs 11 60 adjacent to the ends thereof upon which the mold boards 12 are bolted or otherwise secured. The base plate 10 may in itself constitute the landside bar, or a wear plate 13 constituting the landside proper may be 65 secured thereon by means of bolts 14 which also serve to secure in position adjacent to the furrow side of the base member 10 a tubular upright 15 which is provided with flanges 16 for the passage of the connecting bolts. The upright 15 has an offset 17 on which a sleeve or standard 18 is stepped for rotation about the upright; the latter being threaded at its upper end, as shown, 70 for the reception of a cap member 20 which, 75 after the parts are assembled may be secured by one or more keys 21. The plow beam 22 is associated with the sleeve or standard 18 from which it extends in what may be regarded as a forward direction, said sleeve 80 or standard being provided on its rear side with lugs 23 to support a lever 24 which is fulcrumed between said lugs on a pin or pivot member 25. The sleeve 18 is also provided with rearwardly extending divergent 85 arms or brackets 26 upon which the handles 27 are secured. Beneath the arms 26, the sleeve 18 is provided with a rearwardly extending arm 27' having an upwardly extending lug or cross piece 28 and 90 a transverse notch 29, the purposes of which will be hereinafter explained. The lever 24 is formed with a crank member or extension 30 which constitutes a locking member and which is adapted to engage either one of 95 two oppositely disposed slots 31 formed in the cap plate 20, thereby serving to secure the sleeve or standard carrying the plow beam, the handles and related parts in adjusted position with respect to the upright 100 rising from the base of the device on which the mold boards are supported.

The mold boards are made without the customary wings or rearward extensions, 105 said mold boards being joined together along the line 32, and the wings 33 being suitably assembled together by means of brace members 34, 35 which are extended to form hinge

members 36, 37, the lower hinge member being considerably longer than the upper hinge member 36, as will be clearly seen. The hinge members 36, 37 are connected by 5 pintles or pivot bolts 38 with brackets 39, 40 which are suitably associated with the mold boards 12. It will be seen that the wings 33 may swing from one side to the other, thus causing one of said wings to constitute a rearward extension of one mold board, while the other wing is accommodated between the first mentioned wing and the other mold board in an out-of-the-way and unobstructing position.

15 A combined brace and lock or securing device for the wings is provided, the same including a cap member 41 having an upwardly extending eye 42 and provided at one end with a downwardly extending slotted or bifurcated bracket 43 wherein a lever 44 is mounted on a pivot member 45. One end of the lever member 44 is loosely pivoted in the notch 29 of the arm 27 by a pivot member 46; the other end of the lever member 44 is bifurcated for the reception of 20 one end of a brace member 47. The other end is pivotally connected with the wings 33 at the juncture of the top edges of the latter, said brace member being pivotally connected with the lever member 44 by a pivot member 48. The parts, of course, are so proportioned that when assembled the combined length of the lever member 44 and the brace member 47 will be exactly right to hold the 25 wings in position, as clearly indicated in Fig. 1. The eye 42 of the cap member 41 is connected with the lever 24 by means of a link 49 which is of such length that when the locking member 30 of the lever 24 is in 30 engagement with one of the slots 31, the cap member 41 will be seated upon the cross bar 28 of the arm or bracket 27', thus serving to lock the wings in adjusted position.

When it is desired to reverse the plow, the 35 lever 24 is manipulated to disengage the locking member 30 from the slot 31 with which it is engaged, at the same time lifting and unseating the cap member 41 from the cross bar 28. The standard or sleeve is now 40 free to rotate about the upright 15, being swung around by the beam while the operator walks along with the handle. Owing to the different length of the hinge members 36, 37, the mold board wings, when in 45 position for operation, will gravitate to a slightly tilted position from which, when the device is reversed, they will be displaced by the action of the jointed brace 44, 47, the joint of said brace breaking so as to pass 50 clear of obstructing parts, and the pull on the brace serving to strengthen the latter when the parts have been reversed. The lever 24 is then manipulated to cause the locking member 30 to engage a slot 31, and 55 by the same operation the cap member 41 is

replaced on the cross bar 24, thus locking the mold board wings securely in position.

As will be seen from the foregoing description, taken in connection with the drawings hereto annexed, I have produced a 70 very simple reversible walking plow which may be quickly and conveniently operated, which is not excessively heavy, thereby imposing unnecessary load on the team, and which may be manufactured and marketed 75 at a moderate expense.

Having thus described the invention, what is claimed as new, is:—

1. In a device of the class described, a base member having terminal frogs, an upright rising from the base plate and intermediate the frogs and having an offset at its lower end, the upper end of said upright being threaded, a sleeve stepped on the offset, said sleeve being revoluble about the 80 upright, a plow beam and handles associated with the sleeve, a cap member threaded on the upper end of the upright, and means for locking said cap member against rotation.

2. In a device of the class described, a 90 base member having frogs, mold board members secured thereon, an upright rising from the base, a sleeve revoluble about the upright and having a plow beam and handles, a pair of wings hingedly connected with the 95 mold boards, a bracket extending rearwardly from the sleeve, and a jointed brace connecting the bracket with the wings.

3. In a device of the class described, a base member having frogs, mold board members mounted thereon, an upright rising from the base, a sleeve revoluble about the upright and having a forwardly extending beam, a cap member threaded upon the upright and having oppositely disposed slots, 100 and a locking lever fulcrumed on the sleeve and having a locking member to engage a slot in the cap member.

4. In a device of the class described, a base member having frogs, mold board members secured thereon, an upright rising from the base, a sleeve revoluble on the upright and having a forwardly extending beam, handles connected with and extending rearwardly from the sleeve, a locking lever fulcrumed on the sleeve, a cap member fixed on the upright and having slots engaged by the locking lever, an arm extending rearwardly from the sleeve and having an upwardly extending cross piece, a cap member engaging the cross piece, a link connecting the cap member with the locking lever, a pair of mold board wings joined together and hingedly connected with the mold boards, a jointed brace connecting the wings with the arm extending rearwardly from the sleeve, and a pivot member connecting one member of the jointed brace with the cap member.

5. In a reversible plow, a base member, 130 right and left hand mold board members

supported thereon, extension wings for the mold board members, said wings being joined together and hingedly connected with said mold board members, a member supported revolvably with respect to the base member and including a forwardly extending beam and rearwardly extending handles, means for locking the revolvble member in adjusted position, a jointed brace connect-

ing the revolvble member with the mold board wings, and means for securing said jointed brace in adjusted position.

In testimony whereof I affix my signature in presence of two witnesses.

ZENOS PORTER.
